DESIGN FOR A MIRROR BACK OR SIMILAR ARTICLE

Elizabeth S. Kent, Waterbury, Conn., assignor to Irving Zussman, Brookline, Mass., doing business
under the name and style of Metro Premium Company

Application October 26, 1938, Serial No. 80,672

Term of patent 7 years

To all whom it may concern:

Be it known that I, Elizabeth S. Kent, a citizen of the United States, residing at Waterbury, Connecticut, have invented a new, original, and ornamental Design for a Mirror Back or Similar Article, of which the following is a specification, reference being had to the accompanying drawing forming part thereof.

Figure 1 is a plan view of a mirror back or similar article showing my new design.

Fig. 2 is a side elevation thereof.

The dominant features of my design reside in the portions shown in full lines.

I claim:

The ornamental design for a mirror back or similar article, substantially as shown and described.

ELIZABETH S. KENT.
